CLOSURE MEANS FOR VERTICAL COKING RETORTS

Gettfried Geetz, Webster Groves, Mo., assignor to
Ludwig Kern, Webster Groves, Mo.

Application July 21, 1932, Serial No. 623,703

2 Claims. (Cl. 202—252)

This invention relates to closures, and with regard to certain more specific features, to closures particularly adapted for use in connection with the discharge ends of coking retorts, coke accumulators, and the like.

Among the several objects of the invention may be noted the provision of a closure of the class described which is capable of supporting a heavy load in a relatively gas-tight manner, a closure of the class described including means for manipulation thereof which are easily operated from the exterior of the device to which the closure is applied, and which are adapted to apply force in increased amount, as the doors are closed, at the time at which the increased force is most advantageous; the provision of a closure of the class described which is readily operated in either direction, that is, to open or to close the device to which it is applied; and the provision of a closure of the class described which is relatively simple and economical in construction and operation. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

30 In the accompanying drawings, in which is illustrated one of various possible embodiments of the invention,

Fig. 1 is a top plan view of a closure embodying the present invention;

35 Fig. 2 is a vertical cross section taken substantially on line 2—2 of Fig. 1;

Fig. 3 is a front elevation of the closure shown in Fig. 1; and,

40 Fig. 4 is a view similar to Fig. 3, showing an alternative form of the invention.

Similar reference characters indicate corresponding parts throughout the several views of the drawings.

Referring now more particularly to Figs. 1 and 45 2, numeral 1 indicates generally the walls of a vertical coking retort or the like, which are to be closed at the lower end thereof. It is to be understood that the particular construction of the walls 1 is of no consequence to the present invention.

50 Numeral 3 indicates the doors, or closure itself which is formed in two longitudinal sections adapted, when closed, to completely cover the bottom of the retort. The doors 3 are supported in a preferably cast steel frame 5 (see Fig. 2),

by means of hinges 7. The hinges 7 are provided in suitable number, and of suitable strength, safety to support the weight of the doors 3. The frame 5 is supported, preferably, upon beams 9 such as are provided for the support of the retort walls 1. Together, the frame 5 and the beams 9 may be considered the door frame for the doors 3.

Each of the doors 3 preferably comprises a cast steel section 11 (see Fig. 2), provided in a central portion with a series of deep recesses 13. In the recesses 13 are cast or otherwise secured blocks of refractory material 15, which serve to protect the steel portions 11 against excessive heat within the retort. Around the outer edge of each door 3, and at the ends thereof, a groove 17 is provided. 15 The groove 17 is desirably filled with a sealing material, such as water, oil, asbestos cord, plastic clay, or the like, in order more effectively to make the doors gas-tight in their closed position. The sealing is effected by pressing the material in the groove 17, which thus surrounds the entire discharge end of the retort, between the doors 13 and the frame work 5.

One of the doors 3 is provided on its under side with a flange 19, which overlaps the other door 3 when the doors are in closed position, thereby to make the juncture between the two doors 3 relatively gas-tight.

As will be seen from Fig. 2, the doors 3 swing downwardly on the hinges 7 from their closed position (full lines) to their open position (shown in dotted lines). The swinging of the doors is effected by door-operating means, which will next be described.

Journalized in bearings 21 on the side beams 9 are longitudinal shafts 23. The shafts 23 are preferably slightly eccentric, to provide a slight additional pressure at just the time the doors are closed. Each shaft 23 has keyed thereto, or otherwise secured against rotation, a plurality of 40 door-operating levers 25, each of which carries at its outer extremity or free end 26 a roller 27. In suitable locations on the undersides of the doors 3 to engage the rollers 27 are provided projections or cam surfaces 29, inwardly terminating with notches 30. It will be seen that when the shafts 23 are rotated in such direction as to move the levers 25 in an upward direction, the rollers 27 will engage the projections 29 and thereby force the doors 3 upwardly into closed position, 45 until ultimately the rollers 27 drop into the notches 30, locking the doors closed.

Referring now more particularly to Figs. 1 and 3, it will be seen that the longitudinal shafts 23 extend outwardly from the ends of the retorts. 55

Supported in bearings 31 on the exterior of the retort is a transverse shaft 33, which extends, preferably, throughout the whole length of the retort bench. The shaft 33 is motivated by any suitable means, such as an electric motor. It may be kept continuously rotating, as will be apparent hereinafter.

Also supported on the exterior of the retort, as in bearings 35, is a vertical screw 37 carrying on its lower end a bevel gear 39. Keyed to the transverse shaft 33 in such a manner that rotation relative to the shaft is prevented, but longitudinal sliding on the shaft is permitted, are a pair of bevel gears 41 and 43 adapted to mesh with the bevel gear 39. A lever 45 is provided for each of the bevel gears 41 and 43. By means of the lever 45, either the bevel gear 41 or the bevel gear 43 may be meshed with the bevel gear 39. It will be seen that when the gear 41 meshes with the gear 39, the screw 37 is rotated in one direction, while when the gear 43 is brought into engagement with the gear 39, the screw 37 is rotated in the reverse direction. The gears 41 and 43 are preferably slidable within such range that they may both be disengaged from the gear 39, whereby the shaft 33 may rotate continuously, but whereby the screw 37 may be rotated only at such times as desired.

Carried on the screw 37 is a sliding block or nut 47. The block 47 is prevented from rotating, relative to the screw 37, by a rearward projection 49 (see Fig. 1) which slides in a track 51. It will be seen that as the screw 37 is rotated, the block 47 is moved vertically upwardly or downwardly, depending upon the direction of rotation of the shaft 33. The vertical movement of the block 47 is at a tremendous mechanical advantage over the power delivered by the rotating shaft 33. This vertical movement of the block 47 is used directly to effect opening and closing of the doors 3. The effect is secured by a two-bar linkage comprising links 53 rotatably fixed at one end to the block 47, and pivoted at the other end to lever 55 mounted on the projecting ends of shafts 23. The levers 55 are similar in shape to the door-operating levers 25, and are likewise non-rotatably affixed to the longitudinal shafts 23.

It will be seen that, as the block 47 is raised on the screw 37, the linkages comprising the links 53 and 55 rotate the longitudinal shafts 23 in such direction as to move the door-operating levers 25 upwardly, to close the doors 3. The nearer the block 37 approaches to the top of the screw 37, the slower, in general, the shafts 23 are rotated, because the component of movement of the block 47 that is translated into angular rotation of the shafts 23 becomes decreasingly smaller, but since the force applied to the block 47 does not vary, this means that the force tending to shut the doors 3 increases because it is applied over a lesser angular amplitude. This is distinctly advantageous, as the necessarily tight fit of the doors (in order to secure the gas-tight characteristics) requires the application of more force as the doors approach closed position. When the doors 3 have been completely closed, the gear 41 or 43, as the case may be, is disengaged from the gear 39 by manipulation of the appropriate lever 45. Rotation of the screw 37 then stops, and with it the block 47 stops moving. Inasmuch as the block 47 is near the top of its range of movement, the linkages comprising bars 53 and 55 are most near to their straight position, in which position they have the greatest

holding or locking effect against reopening of the doors 3. This enhanced holding effect is particularly advantageous when it is considered that, in this position, the doors must support the weight of the entire charge placed in the retort.

Opening of the doors is accomplished by meshing the other of gears 41 or 43 with the gear 39, in such manner that the screw 37 is rotated to move the block 47 downwardly. Downward movement of the block 47 rotates the longitudinal shafts 23 into such directions, respectively, that the door-operating levers 25 are moved downwardly. After a relatively slight movement, the rollers 27 disengage from the projections 29 on the doors 3, and the doors 3 are thereafter free to fall open under their own weight as quickly as the levers 25 are rotated out of the way. In their fully open position, the levers 25 hang almost vertically downwardly (see dotted lines, Fig. 2) and the doors 3 hang open in a similar vertical position, leaving the lower end of the retort completely open and free of obstruction. This complete opening is necessary in the case of the ordinary lump coke retorts, as the charge in the retort falls therefrom in a substantially single, large block. If the closure is to be used for briquette coking retorts, it is not necessary that the doors 3 open all the way, as the briquettes are fully capable of discharging through only partially open doors, that is, doors open more to a funnel shape.

It will be apparent that the sliding block and screw method of operating the longitudinal door-operating shafts 23, is but one of the number of methods which may be used. For example, in Fig. 4 there is shown an electrical method of operating, which comprises a vertical solenoid 57 having a movable core 59 to the ends of which the links 53 are pivoted. By applying more or less current to the solenoid 57, the core 59 may be drawn therein to a greater or less extent, thus operating the links 53 and subsequently the shafts 23 in the same manner as in the case of the sliding block and screw embodiment.

Similarly, the sliding block and screw arrangement may be substituted by a hydraulic cylinder and piston, arranged in the same general manner as is solenoid 57 in Fig. 4. It is thus apparent that the invention is independent of the particular power means used for operating the doors.

The present invention is particularly adapted for use in connection with the vertical coking retorts described and claimed in my co-pending patent applications, Serial Numbers 623,700 and 623,701, filed July 21, 1932.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. Closure means for vertical coking retorts comprising a pair of oppositely swung doors hinged to open downwardly from the sides of an opening to be closed, said doors being so shaped that together they completely close off the opening when in a closed position, a pair of shafts allocated one for each door, means supporting said shafts parallel to, but beneath the hinged axis of said doors and at least one lever non-rotatably

secured to each of said shafts, said lever having a free end, a roller on said free end adapted to engage and slide upon the under side of its respective door, whereby, when said shafts are rotated in the direction of closing of their respective doors, said rollers engage and slide upon the under surface of said doors to force said doors into a closed position, a motivated vertical screw, a sliding block moved vertically by said screw, a lever non-rotatably secured to the end of each shaft, and a link rotatably joining the end of each such lever to the sliding block, whereby, upon vertical movement of said block, said shafts are rotated in the desired direction in such manner that, as the doors approach a closed position, the rotation of the shafts is at a decreased velocity providing greater closing force upon the doors.

2. Closure means for vertical coking retorts comprising a pair of oppositely swung doors

hinged to open downwardly from the sides of an opening to be closed, said doors being so shaped that together they completely close off the opening when in a closed position, a pair of shafts allocated one for each door, means supporting said shafts parallel to, but beneath the hinging axis of said doors, and at least one lever non-rotatably secured to each of said shafts, the under side of each door being provided with a cam surface, the said lever having a free end, a roller on said free end adapted to engage and slide upon said cam surface, whereby when said shafts are rotated in the direction of closing of their respective doors, said rollers engage and slide upon said cam surfaces to force said doors into a closed position, each of said cam surfaces including a notch into which the roller fits when the door is in a fully closed position.

GOTTFRIED GOETZ.
